UNITED STATES PATENT OFFICE.

EVERETT R. BURTNELL, OF LOS ANGELES, CALIFORNIA, ASSIGNOR, BY DIRECT AND MESNE ASSIGNMENTS, TO THE AUTOMOTIVE VALVES CO., OF LOS ANGELES, CALIFORNIA, A VOLUNTARY TRUST.

INTERNAL-COMBUSTION ENGINE.

Application filed January 12, 1925. Serial No. 1,848.

My invention relates to internal combustion engines and has for its principal objects, the provision of a relatively simple, strong, rugged and efficient two stroke cycle internal combustion engine, wherein six cylinders are arranged to form three units that combine and function for the output of power, three of the six pistons that operate within the six cylinders being of one form and weight, the other three pistons being of a different form and weight; to arrange the cylinders and pistons in three pairs, a set of pistons of different size and weight, the two pistons constituting each pair being separately connected to one throw of a three throw crank shaft and, further, to arrange the three throws of the crank shaft 120° apart so as to provide reciprocatory and rotary balance.

Further objects of my invention are to provide an improved two stroke cycle internal combustion engine wherein three units of each function are employed; to provide an engine of the character referred to having the six cylinders arranged with their axes parallel, in the same plane and in a row parallel with the axis of the crank shaft; to form three of the cylinders with chambers with uniform diameter and the other three cylinders having two diameter chambers, one straight or uniform diameter bore cylinder and a two diameter bore cylinder being disposed immediately adjacent to each other end forming one of the three pairs of cylinders of the engine; to connect the head ends of the members of each pair of cylinder chambers by a common compression and combustion clearance chamber; to provide four main bearings for the three throw crank shaft with one throw between each pair of main bearings; to provide each of the three throws of the crank shaft with two connecting rod bearing peripheries and to arrange centrally, on each throw and between the bearing peripheries thereon, a counter balancing weight that is positioned so that it projects diametrically opposite to the radial plane occupied by the crank to which it is connected.

Further objects of my invention are to provide three piston valves for controlling the admission of gaseous fuel to the larger diameter chambers of the cylinders having the two diameter chambers and pistons; to

arrange said piston valves with their axes centered in a row or plane that is parallel with the plane occupied by the axes of the engine cylinders; to actuate said piston valves from an auxiliary or eccentric shaft that is driven positively from and at the same speed with the engine crank shaft; to provide the engine with a detachable cylinder head block, in which is formed the three common compression and combustion clearance chambers that connect the head ends of the respective members of the three pairs of combustion chambers; to arrange ignition means in each clearance chamber in said head and further, to form in the engine cylinders, inlet and exhaust ports that are located so as to bring about the maximum degree of efficiency of engine operation and power output.

With the foregoing and other objects in view, my invention consists in certain novel features of construction and arrangement of parts that will be hereinafter more fully described and claimed and illustrated in the accompanying drawings in which:

Fig. 1 is a vertical section taken lengthwise through the center of an engine constructed in accordance with my invention.

Fig. 2 is a diagrammatic view that graphically illustrates the relative angular positions of the crank throws of the crank shaft.

Fig. 3 is an enlarged vertical section taken approximately on the line 3-3 of Fig. 1.

Fig. 4 is a horizontal section taken approximately on the line 4-4 of Fig. 1.

Fig. 5 is a horizontal section taken approximately on the line 5-5 of Fig. 1.

Referring by numerals to the accompanying drawings, 10 designates a cylinder block, 90 preferably cast in a single piece and within which are formed six bores, 11, 12, 13, 14, 15 and 16, that function as combustion chambers. The axes of these chambers are parallel and they are arranged "in row", that is, 95 said axes all occupy the same plane.

The diameters of bores or chambers 11, 13 and 15 are straight or uniform throughout their lengths, while the alternate bores or chambers 12, 14 and 16 have their lower portions increased in diameter to form gaseous fuel pumping chambers 17, 18 and 19 respectively.

Secured in position on the head end of

block 10 is a head block 20, in the underside of which is formed three chambers 21, 22 and 23.

- Chamber 21 is located so that it connects 5 and provides a common compression and combustion clearance for combustion chambers 11 and 12 and in similar fashion, chamber 22 connects and provides a common clearance for combustion chambers 13 and 14. 10 The third chamber 23 is located so that it connects and provides a common compression and combustion clearance for combustion chambers 15 and 16.

Head 20 is preferably formed with connected cells or chambers 24, that may be connected in any suitable manner with cells or chambers 25, that are formed in the upper portions of the walls of cylinder block 10 and which cells are for the accommodation of a 20 circulating cooling fluid medium, such as water.

Seated in head 20 and projecting into the common clearance chambers 21, 22 and 23 are ignition devices, such as spark plugs 26, there being, preferably, two plugs to each chamber.

Journalled in four main bearings 27, that are formed in a crank case 28 is a crank shaft 29, the axis of which intersects the parallel axes of the six cylinders in block 10 and said 30 crank shaft is provided with three cranks, 30, 31 and 32, that are disposed 120° apart.

Crank 30 is located in line with chambers 11 and 12, crank 31, in line with chambers 13 and 14, and crank 32 is in line with chambers 35 15 and 16.

Each crank throw of the crank shaft is provided with two finished bearing peripheries, such as 33 that are engaged by the connecting rods to the pistons in the respective 40 chambers and secured to the central portion of each crank throw, between the connecting rod bearing faces thereon is a counterbalancing weight 34. Each of these counterbalancing weights projects diametrically opposite to the radial plane occupied by the crank to which it is connected and thus the three weights are disposed 120° apart, circumferentially.

Straight diameter pistons, such as 35 are 50 arranged for operation within combustion chambers 11, 13 and 16 and similar pistons 37 are arranged for operation within the combustion chambers 12, 14 and 15.

The lower portions of the last mentioned 55 pistons 12, 14 and 16 are provided with enlarged skirt portions 38 that function as pistons within the corresponding chambers 17, 18 or 19, of increased diameter, and all of the six pistons are connected to the corresponding bearing peripheries 33 on the respective crank throws by connecting rods 36.

Arranged on one side of block 10 and directly opposite chambers 12, 14 and 16 are piston valve cylinders, such as 39, the axes of 65 which are parallel with the axes of the en-

gine cylinders and arranged for operation within each cylinder 39 is a piston valve, such as 40. All of these piston valves are connected to an auxiliary or eccentric shaft 41 by connecting rods, such as 42 and said auxiliary shaft, which is mounted for rotation in suitable bearings, is driven directly from and at the same crank speed of crank shaft 29, preferably by means of conjoined gear wheels, such as 43.

Formed through the upper portion of the wall of each valve cylinder 39 is a gaseous fuel inlet port 44, which may be connected to a suitable source of supply such as a carburetor and leading from the upper end of the chamber in each valve cylinder to the upper portion of the annular pumping chamber of the adjacent two diameter cylinder is a short gaseous fuel inlet duct 45.

On the opposite side of block 10 from the piston valves, exhaust ports 46 lead from the intermediate portions of combustion chambers 11, 13 and 15, said ports being disposed so that they are uncovered and open, only when the pistons 35 are at the lower or outer ends of their strokes.

Formed in the walls of block 10 that surround the intermediate transfer portions of combustion chambers 12, 14 and 16 are annular gaseous fuel transfer chambers 47 and leading therefrom into said combustion chambers 12, 14 and 16, are gaseous fuel inlet ports 48. These ports are disposed so that they are uncovered and open only when the pistons 37 that operate in the chambers 12, 14 and 16 are at the outer or lower ends of their strokes.

Leading from the upper portions of the annular pumping chambers 17, 18 and 19 are gaseous fuel outlet ports, such as 49 and leading from the outlet port that leads from chamber 17 to an inlet port 50 that communicates with the transfer chamber 47 that surrounds combustion chamber 16, is a transfer duct 51.

Leading from the outlet ports 49 that lead from pumping chamber 19 to the inlet port 50 into annular chamber 47 that surrounds combustion chamber 14, is a transfer duct 52 and a similar transfer duct 53 that leads from the gaseous fuel outlet ports from pumping chamber 18, to the inlet port 50 of transfer chamber 47 that surrounds combustion chamber 12.

For a more comprehensive understanding 120 of these transfer ducts and their functions, reference may be had to U. S. Letters Patent No. 1,624,583, issued to me April 12, 1927.

In the operation of my improved engine, 125 it will be understood that the three pairs of cylinders with their respective pistons and piston valves function as three units and that on the upward or inward stroke of each piston 37, a charge of gaseous fuel is compressed in the corresponding chamber 17, 18 or 19 and 130

passes therefrom through the corresponding transfer duct to the corresponding one of the annular chambers 47 and the combustion chambers that are surrounded thereby.

5 As each piston valve moves through the lower half of its downward stroke and through the first half of its upward stroke, piston 37 in the adjacent and associated engine cylinder, is moving downward thereby 10 inducing into the corresponding annular chamber, for instance 17, through open inlet port 44, piston valve chamber and duct 45 a charge of gaseous fuel and, on the following upward stroke of piston 37, this charge of 15 gaseous fuel will be forced under pressure from chamber 17 out through port 49, through duct 51 and port 50, into chamber 47 that surrounds combustion chamber 16.

In like manner, gaseous fuel is pumped 20 from chamber 19 through duct 52 to chamber 47 surrounding combustion chamber 14, and gaseous fuel pumped from chamber 18 passes through duct 53 to chamber 47 that surrounds combustion chamber 12.

25 As each pair of pistons 35 and 37 reach the lower or outer end of their stroke, the corresponding inlet and exhaust ports 48 and 46 are uncovered, and immediately the charge of gaseous fuel that has been precompressed to 30 a certain degree within the corresponding chamber 47 will pass through ports 48 into and upwardly through the corresponding combustion chamber, for instance, chamber 12 and from the latter, the gaseous fuel will 35 pass through common clearance chamber 21 and thence downwardly through combustion chamber 11.

The charge of fresh gaseous fuel thus 40 pumped into connected chambers 11 and 12 will drive before it the burnt gases and products of combustion resulting from the previously ignited fuel charge and said burnt gases will be forced out through the exhaust port 46 that leads from chamber 11, after the 45 pistons 35 and 37 have moved a short distance upward or inwardly, ports 46 and 48 will be covered and closed and during the continued upward or inward travel of said pistons, the admitted fuel charge will be compressed within 50 the upper portions of chambers 11 and 12 and within common clearance chamber 21. At the point of highest compression or as the 55 pistons pass high center, the compressed fuel charge will be simultaneously ignited at two different points within chamber 21 by sparks produced between the inner ends of the electrodes of plugs 26, and the abrupt rise in 60 pressure following combustion of the compressed fuel charge will be directed against the heads of pistons 35 and 37 to drive the same downward on their power stroke.

It will be understood that the operations just described take place within the connected pairs of cylinders 13 and 14 and, 15 and 16, and, as there are three units to the

engine, and the three crank throws to which the pairs of pistons are connected are disposed 120° apart there will be three power impulses imparted to the crank shaft during each revolution thereof.

The piston valves 40 operate in proper time relation to the combined power and compression pistons with which they are associated and the symmetrical disposition of the three throws of the crank shaft and the 75 counterbalancing of each throw, tends to eliminate vibration and insures reciprocatory and rotary balance.

Obviously, minor changes in the size, form and construction of the various parts of my 80 improved internal combustion engine may be made and substituted for those herein described without departing from the spirit of the invention, the scope of which is set forth in the appended claim.

I claim as my invention:

In a two stroke cycle internal combustion engine, the combination of six cylinders arranged with their axes parallel and centered on a line and in a row parallel with the axis 90 of the engine crank shaft, three of the six cylinders having straight diameter, the other cylinders of the two diameter form, the six cylinders being arranged in three pairs with one straight diameter bore and one two diameter bore cylinder being disposed adjacent each other and comprising one pair, a single compression and combustion clearance chamber joining each pair of cylinders as a common clearance chamber to both, a three throw 95 crank shaft mounted in four main bearings, a crank throw between each pair of main bearings, the three throws of the crankshaft being disposed 120° apart, there being two connecting rod bearing faces on each of the three crank throws of said crank shaft, a counter balance weight arranged centrally between the two crank bearing faces of each of the three crank throws and suspended 100 diametrically opposite the axes of the said crank throws, an auxiliary shaft, three piston valves directly connected to said auxiliary shaft, said auxiliary shaft being driven at engine crank shaft speed, the three piston valves arranged with the axes of their respective bores substantially parallel with the axes of the main cylinders and arranged in a row centered on a line parallel with the axis of said auxiliary shaft, one piston valve being disposed directly adjacent to each of the main cylinders having the two diameter bore and functioning as an admission valve to the annular space created between the stepped diameters of the two diameter cylinder and its respective two 110 diameter piston, each piston valve chamber being provided with a gaseous fuel supply a short distance below its head end where said port is fully open only when the corresponding piston valve is at the lower end of its 115

120 diameter piston, each piston valve chamber being provided with a gaseous fuel supply a short distance below its head end where said port is fully open only when the corresponding piston valve is at the lower end of its 130

stroke, there being an inlet port leading from the extreme head end of each piston valve chamber into the extreme upper end of the chamber of larger diameter in the corresponding two diameter pumping cylinder, said inlet port being disposed diametrically opposite to the outlet port that leads from the chamber of larger diameter of said two diameter pumping chamber, a detachable cylinder head having three common compression and combustion clearance chambers arranged and located so as to join the respective members of the three pairs of cylinders, a pair of ignition devices seated in the engine cylinder head and projecting into a common clearance space, one ignition device being located above each cylinder, exhaust ports formed in the wall of each of the straight diameter cylin-

ders, inlet ports formed in the wall of the smaller diameter portion of each of the two diameter cylinders, inlet and outlet ports formed in the head of the larger diameter portion of each two diameter cylinder dual ignition means located in the clearance chamber that connects each pair of cylinders and an externally arranged fresh charge transfer duct arranged between the pump chamber of each two diameter cylinder with the combustion chamber of another one of the pairs of cylinders and which combustion chamber to which the transfer duct is connected being the smaller diameter portion of one of the two diameter cylinders.

In testimony whereof I affix my signature.

EVERETT R. BURTNETT.
